GARMENT POCKET

Irving M. Falk, Philadelphia, Pa., assignor to The Nu Pocket Method Co., Philadelphia, Pa.

Continuation of application Serial No. 176,988, August 1, 1950. This application October 14, 1953, Serial No. 385,997

2 Claims. (Cl. 2—247)

My invention relates to a new and useful garment pocket and more particularly has to do with the assembling of a side pocket in such garments as work and play pants, overalls and the like for use by men, women and children.

This application is a continuation of my application Ser. No. 176,988, filed August 1, 1950.

An object of this invention is to provide an inexpensive and novel method of assembling bagged pockets in low priced garments such as are used by workingmen in contradistinction to dress garments.

Another object of the invention is to provide a side pocket for work garments in which the entrance or access opening is along one edge of a placket to one side of the pocket at or near the upper end thereof.

A further object of this invention is to secure side edges of the pocket in a seam provided, either between two contiguous sections or at a placket edge of a garment.

A still further object of the present invention is to combine or interengage parts of a garment and pocket in a unique manner to produce a novel structure.

With the above and other objects in view this invention consists of the details of construction and combination of elements hereinafter set forth and then designated by the claims.

In order that those skilled in the art to which this invention appertains may understand how to make and use or employ the same I will describe its construction in detail, referring by numerals to the accompanying drawings forming a part hereof, in which:

Figure 1 is an inside elevational view of a portion of a pair of pants, intended especially for women's wear, showing my new pocket construction;

Fig. 2 is an outside elevational view of the construction shown in Fig. 1;

Fig. 3 is a vertical cross-sectional view taken on the line 3—3 of Fig. 1;

Fig. 4 is a horizontal cross-sectional view taken on the line 4—4 of Fig. 2;

Fig. 5 is a horizontal cross-sectional view taken on the line 5—5 of Fig. 2;

Fig. 6 is an inside elevational view of a portion of a pair of pants of the overall or jumper type, intended especially for men's wear, showing my new pocket construction;

Fig. 7 is an outside elevational view of the construction shown in Fig. 6;

Fig. 8 is a vertical cross-sectional view taken on the line 8—8 of Fig. 6;

Fig. 9 is a horizontal cross-sectional view taken on the line 9—9 of Fig. 7; and

Fig. 10 is a horizontal cross-sectional view taken on the line 10—10 of Fig. 7.

Referring first to Figs. 1—5, in carrying out my invention as herein embodied 15 represents a pocket produced from a strip of suitable material folded upon itself along a substantially vertical line to provide a fold 16 with the bottom portions of the side edges and the lower edges

2

of the two pocket layers 17 and 18, Fig. 3, coinciding and enclosed in a folded strip or binding 19. The said lower portions of the side edges and said lower edges of the pocket material and the binding are sewn together 5 by the two parallel rows of stitches 20.

The free upper corner of the outer pocket layer 18 is cut away to provide an oblique edge which will be attached to a wall edge of the pocket opening, to be presently described. A facing strip 21 of garment material, 10 of greater dimensions than the cut away portion of the outer pocket layer, is partially sewn on the inside face of the inner pocket layer 17 by stitches 22 in opposed relation to the cut away portion of the pocket layer 18.

As illustrated in Figs. 1, 2 and 3, the reference numerals 15 23 and 24 represent two contiguous garment sections and one of these, as 23, has the upper corner adjacent the garment section 24 cut away on a generally oblique line to form a substantially diagonal edge which is turned in upon itself to provide the folded finished edge 25.

20 Prior to the garment sections being joined together the oblique edge of the pocket layer 18 is inserted in the fold of the diagonal edge of the garment section 23 and permanently sewn in place by the stitches 26. Then the garment sections are assembled so that the meeting 25 edge of section 23 and the upper portion of the free side edge of the pocket layer 17, with the facing strip 21, overlap the meeting edge of the garment section 24 and all of the cooperating parts, including both layers of pocket material a short distance below the folded edge 25, are sewn together by the stitches 27. Finally, an inside waist band 28 and a coinciding outside waist band 29 which embrace upper parts of the pocket and garment sections are sewn in place by the stitches 30 and 31, the latter, at least, engaging the pocket elements to assist in 35 supporting the pocket.

While the oblique edges of one pocket layer and one garment section are sewn together they are free from other parts so that between the finished diagonal folded edge and the other pocket layer, with the finishing strip 40 thereon, the pocket opening or entrance 32 is provided.

In the embodiment of the invention shown in Figs. 6—10, the reference numerals 33 and 34 represent two contiguous garment sections and one of these, as 33, has the upper corner adjacent the garment section 34 cut 45 away on a generally oblique line to form a substantially diagonal edge which is turned in upon itself to provide the folded finished edge 35 similar to the one previously described except that the edge 35 is shown straight instead of curved.

Before the garment sections are joined together the oblique edge of one pocket layer is inserted in the fold of the diagonal edge of the garment section 33 and permanently sewn in place by stitches 36. Next, the garment sections are assembled so that the meeting edge 55 of garment section 33 overlaps garment section 34 and the two are sewn together between the bottom of the garment and the hip by the stitches 37 leaving an open placket 38 from the hip to the waist line and constituting the pocket opening or entrance which placket may be 60 closed and secured by suitable fastening devices. While buttons and buttonholes are shown as the fastening devices, hook fasteners or "Zippers" can be substituted therefor. From the hip to the waist line, or above in some instances, a supporter strip 39 is sewn on the inturned edges of the front garment section and the facing strip 21 by stitches which may be a continuation of the stitches 37. The supporter strip 39 is the equivalent of the part of one of the garment sections previously described and has a similar purpose.

70 In lieu of the outside waist band a bib member 40 overlaps the upper ends of the garment sections and the exposed part of the facing strip 21 and is sewn in place

with an inside waist band 41, the lower edge of which is folded in, by means of stitches 42. The upper two layers of the pocket beyond or forward of the opening, entrance or placket are disposed between the inside waist band 41 and other elements of the garment, such as the bib member and garment section 33.

An important advantage of the new construction will be evident, it is believed, from Figs. 2, 3, 4, 7 and 9. As there shown, the entrance or opening to the pocket, designated 32, is defined by hemmed portions of the fabric which present no abrupt shoulders or transverse edge planes of fabric that would be susceptible to wear from the act of inserting and removing the hand of the wearer, or insertion and removal of anything else. As is well known, pocket openings generally fail in this respect before the material of which the pocket itself is made shows any noticeable wear. As compared with the conventional or best prior art constructions, the new construction reduces the surfaces that are rubbed in use of the pocket and confines these surfaces to locations where such wear as does occur will be largely hidden so that threadbare areas and loose ends of broken thread will not be noticeable to the person wearing the garment or to others. Thus, the edge A in Fig. 4 offers no obstruction to entry or removal of a hand into or from the pocket, nor does the area B in this figure. The same is true of the portions C and D in Fig. 9.

Moreover, the new relationship of the superposed portions of the margins of the inner pocket layer, the facing strip and the rear section of the garment, comprising the edge A in Fig. 4 or C in Fig. 9, forming as they do a shoulder facing to the rear of the garment outside the pocket, disposes the margin of the facing strip in such a way that the facing strip extends in a flat, smooth and uninterrupted plane from the pocket, over the superposed portions, clear up to said shoulder. This eliminates the dust-catching external shoulder that would otherwise be formed facing forwardly, into the pocket. Such a shoulder is objectionable because it collects lint, dust and the like from the pocket and from objects carried in the pocket, from the repeated movement of the wearer's hands into and out of the pocket. Such collection soon forms a noticeable line of light color embedded in the shoulder and requiring thorough brushing, if not indeed very strenuous digging, to clean it out. It will be obvious that no such line of dust, lint and the like can form in the present construction because the only external shoulder here involved is one facing out of the pocket, to the rear of the garment, where it cannot catch any dust, lint and the like from the pocket or from objects put into or taken from the pocket. This is regarded as an important feature of the new construction.

From the foregoing it will be obvious to those skilled in the art of manufacturing work and play pants, overalls, dungarees, jeans and the like that I have provided an exceedingly simple and inexpensive pocket structure and method of attaching the same to garments of the class mentioned.

Having described my invention what I claim as new and useful is:

1. A pocket for pants comprising in combination front and rear garment sections having side edges secured together in overlapping relation from the bottom of each leg to a location in the region of a hip portion to form a side seam, said garment sections being free and unconnected with each other above the hip portion and the free corner of the front section above the hip portion being folded inwardly to form a turned edge for a pocket opening, a pocket including substantially parallel inner and outer layers having the bottom and front side edges closed, a facing strip secured to the inner pocket layer adjacent the free rear edge of said inner layer with the rear edge of said facing strip folded inwardly over the contiguous free edge of said inner layer, and said facing strip and enclosed edge of the inner pocket layer overlying the edge portion of the rear garment section, the said edge portion of the rear garment section being reversely turned and positioned between folded portions of the inner pocket layer, and a line of stitching extending through the superposed portions of said folded portions of the inner pocket layer, the superposed portions of the front and rear sections and the facing strip, whereby at the region of the pocket said superposed portions of the inner pocket layer, the rear section and the facing strip form a shoulder facing to the rear of the garment beyond the pocket, with the margin of said facing strip extending in flat, smooth and plane form from within said pocket, over said superposed portions, up to said shoulder.

2. The combination claimed in claim 1, in which said front garment section has its rear edge portion turned forwardly and positioned between the folded-in portions of the facing strip and the rear garment section.
